UNITED STATES PATENT OFFICE

CHARLES S. HEMPSTEAD, OF NEW SALEM, PENNSYLVANIA, ASSIGNOR OF ONE-HALF
TO WILLIAM B. WHARTON, OF PITTSBURGH, PENNSYLVANIA

CLAMP FOR POSITIONING METALLIC CURB EDGING

Application filed October 31, 1928. Serial No. 316,292.

This invention relates to a clamp to be used in positioning metallic edges for roadway curbs and the like.

In supporting metallic edges or cornices for curbs, a great deal of difficulty has been experienced in positioning and maintaining them in proper alignment while the concrete is being poured into the usual curb forms.

The object of this invention is to provide a clamp of simple structure which may be readily utilized to position and fix metallic edges for curbs during pouring of the concrete to form the curb proper.

In the accompanying drawings Figure I is a fragmentary plan view of a portion of a cement road, showing the curb forms positioned adjacent one edge thereof, and showing clamps of the present invention in position to retain the metallic curb edging; Figure II is a sectional view taken on the line II-II of Fig. I; Figure III is an enlarged view of a slightly modified form of the clamp of the present invention; Figures IV and V are respectively a side elevation and a plan view of a still further modified form of the clamp; and Figure VI is a sectional view, similar to that of Fig. II, showing a clamp adapted to retain a curb edging of a slightly modified cross section.

The reference numeral 1 denotes a portion of solidified concrete road-bed upon and adjacent which are fixed the metallic curb forms 2 and 3. The cement to form the curb is poured into the space 4 between the said two curb forms. It is common practice to provide the cross members 5, which are fastened, as shown, to secure in spaced relation the aforesaid forms. The metallic curb edging 6 usually is positioned adjacent the inner upper edge of the form 3, so that when the concrete is poured and allowed to harden, the edge 6 is embedded at the upper and inner edge of the curb.

In Figures I, II and III the curb edging illustrated is curved in cross section and presents an outer rounded corner for the finished curb. It is ordinarily difficult to position this type of curb edging, but with the aid of the clamps 7 this difficulty is eliminated.

The particular shape of inner portions of

the clamps 7, which engage the metallic edging 6 is of prime importance. It will be noted that the clamps are constructed to form the corner 8, which receives the edge 6^a of the curb edging member 6, and the clamp is provided with the inturned portion 9. This portion 9 is so formed, and is of such length that it engages the lower edge 6^b of the edging member 6. When the clamps 7 are positioned on top of the curbing form 3, and the tightening wedges 10 hammered into position, as illustrated in the drawings, the edge 6^b is drawn flush with the inner surface 3^a of the form member 3, and since the central portions 7^a of the clamps rest on the upper surface of the form 3, the edge 6^a will obviously be aligned with the top surfaces of the form members 2 and 3. In this manner the curb edging 6 may be retained in the desired position while the concrete is being poured into the space 4.

Therefore, it may readily be understood that the clamp is shaped so that the edging member 6 is positioned at the proper angle and at the proper elevation. After pouring, the concrete in the form members 2 and 3 is smoothed along its extent, forming an upper surface which lies parallel to the top surfaces of the form members, and manifestly the edge 6^a will be flush with the upper surface of the concrete.

After the poured concrete is set or partially hardened, the clamps may be torn out without disturbing the curb edging, and the resulting holes in the concrete may be easily patched and smoothed over.

Although the wedges 10 serve well for drawing the clamps 7 tightly into position on the form 3, it should be understood that the threaded clamp member 11, shown in Fig. III, or the arrangement of the eccentrically mounted wheel 12, shown in Figures IV and V, may serve as modifications of the means for tightening the clamps in position.

Figure VI shows a clamp 13, which is constructed with the same general shape as the clamp 7; the end portion 13^a is slightly modified, however, to suitably position the curb edging 14. This curb edging has a structural angle cross section, but it is positioned and maintained similarly to the edging 6.

Due to the difficulty experienced in the past in mounting curb edgings, there has been a tendency to avoid their use. However, their usefulness is well known in preserving curbs, and the clamp of the present invention makes it commercially possible to mount the curb edgings with little difficulty, and the clamp is therefore of great utility.

What I claim is:

- 10 1. In combination with a curbing-form a clamp including a central portion seated on the curbing-form and an end portion extending downwardly from one end thereof and spaced from the inner surface of said curbing-form, together with an inturned portion extending from said end portion into contact and cooperating with the said inner surface of the curbing-form.
- 20 2. In combination with a curbing-form a clamp including a central portion seated on the curbing-form, and an end portion extending downwardly and an inturned portion extending therefrom, the central and end and inturned clamp portions cooperating
25 with the inner surface of said curbing-form to position and retain members as described.

In witness whereof, I hereunto set my hand.

CHARLES S. HEMPSTEAD.
